UNITED STATES PATENT OFFICE.

MARCELLUS B. WILLCOX, OF CLEVELAND, OHIO, ASSIGNOR TO THE PECK, STOW & WILCOX COMPANY, OF SOUTHBURY, CONNECTICUT.

DESIGN FOR A COFFEE-MILL BOX.

SPECIFICATION forming part of Design No. 18,243, dated April 3, 1888.

Application filed November 18, 1887. Serial No. 255,560. Term of patent 14 years.

To all whom it may concern:

Be it known that I, MARCELLUS B. WILLCOX, a citizen of the United States, residing at Cleveland, in the county of Cuyahoga and State of Ohio, have invented and produced a new and original Design for a Coffee-Mill Box, of which the following is a specification, reference being had to the accompanying drawing, forming part thereof, in which the only figure is a perspective view of my newly-designed box for coffee or spice mills.

Heretofore the boxes of these mills have generally been made with the body portion square in plan view and with angular corners. A prior patent also shows the body portion, top, and base as formed with rounded corners.

In my mill, A designates the body portion, B the cap, and C the base. The corners *a* of the body portion are rounded, while the base C, which projects beyond the sides of the body, is square, as viewed in plan view. The projecting portions or edges of the base C, when viewed in side view, slant from the bottom upward and inward toward the body, as shown, the said edges of the four sides of said base having the miter-corners *b* at their junction.

There is a narrow flat border surrounding the body A on the top of the base C, which, at the junction of the square corners of the base and rounded corner of the body, forms nearly a complete triangular figure of peculiar form, curved on one side and straight on two sides, as shown.

I claim—

The design for a coffee or spice mill box herein shown and described, the same consisting of cap B, the body portion A, having the rounded corners *a*, and the projecting base C, having a square contour in plan view, and having the projecting edges slanting from the bottom inward and upward, with the miter-corners *b* at their junctions, and having also the narrow flat border surrounding the body on the top of the base, which, at the junction of said square corners of said base and rounded corners of the body, is in the form of nearly a complete triangular figure having one curved and two straight sides.

MARCELLUS B. WILLCOX.
